APPARATUS FOR COATING MATERIAL IN STRAND FORM

Wilson W. Rea, Chatham, and Joseph E. Wiltrakis, Plainfield, N. J., assignors to Western Electric Company, New York, N. Y., a corporation of New York

Application December 24, 1941, Serial No. 424,274

13 Claims. (Cl. 91—59.4)

This invention relates to apparatus for coating material in strand form.

In the coating of a strand with a bath of liquid material and particularly in coating a metal wire by passing it through a bath of molten metal, a chief problem has long been that of removing excess coating material from the strand as it emerges from the coating bath, and many apparatuses and devices have been originated for that purpose. A particular case of this general character, and one having particular problems, is that of effectively coating with metallic tin copper wires for use in telephone cables and apparatus. An enormous quantity of such tinned wire is used for these purposes every year. At the present time, when there is difficulty in procuring sufficient tin for all of the nation's varied needs, the problem becomes pressing of reducing the coating to the least practicable thickness while ensuring its complete continuity. In some cases the ordinarily entirely satisfactory wiping dies of metal are not entirely satisfactory when applied to produce minimum thickness coatings because they may take no account of small inevitable variations of wire diameter and hence tend to produce coatings unnecessarily thick on thinner portions of wire and too thin or even not wholly continuous on thicker portions.

An object of the present invention is to provide coating apparatus for strands which shall be simple and reliable and shall act efficiently to produce on the strand a coating of exceptional thinness but yet wholly continuous and substantially uniformly thick.

With the above and other objects in view, the invention may be embodied in a device for wiping a strand emerging from a bath of liquid coating material, which device comprises means to remove the major portion of the liquid from the strand and a wiping strand passing around the coated strand in one or more coils and advancing continuously longitudinally of itself and transversely to the coated strand to continuously present fresh wiping surfaces, the wiper strand being under adjustable longitudinal tension to control the severity of the wiping action.

Other objects and features of the invention will appear from the following detailed description of one embodiment thereof taken in connection with the accompanying drawing, in which the same reference numerals are applied to identical parts in the several figures and in which

Fig. 1 is a diagrammatic view in longitudinal vertical section of an apparatus constructed in accordance with the invention; and

Fig. 2 is a similar view on an enlarged scale of the wiper strand and its associated elements.

The apparatus herein disclosed as an illustrative embodiment of the invention has for its purpose the tin coating of copper wire particularly, though with slight and obvious modifications it could well be applied to coating almost any analogous strand with almost any liquid material. The apparatus comprises a strand supply means, e. g. a reel 10, from which the wire 9 to be coated is drawn by a capstan 11 in the direction indicated by arrows and is wound, after being coated, on a take-up means, e. g. a reel 12. Leaving the supply reel 10, the strand 9 (hereinafter called 15 the core or the coated core to avoid confusion with the wiper strand) presses through a cleaning means such as a pickling bath or a bath 14 of soldering fluid 15. Thence the cleaned core passes through a bath 16 of liquid coating material, e. g. 20 molten tin 17. The core is submerged in the molten tin bath by passing under a roller 18. Emerging from the tin, the core passes through a preliminary wiping die 19, preferably a perforated disk of steel or other suitable material, to 25 remove the major portion of the excess tin carried by the core. The coated and partially wiped core then passes through one or more turns of the wiper strand 20 and thence through a cooling bath 30 21 of suitable liquid, e. g. water 22, to the capstan 11 and take-up 12.

The wiper strand 20 is preferably a soft spun cord of textile material, e. g. cotton, linen, wool, artificial fiber or the like, and is drawn from some suitable supply (not shown) in the direction indicated by arrows and enters a tank 24 of liquid, here a lubricant oil 25, entering and leaving through guide slots 26. The strand 20 is forced to submerge in the oil by passing under a block 27 eccentrically pivotally supported at 28. Forward 35 of the pivot 28, the strand 20 and the block 27 resting on the strand are supported by a transverse bar 29. As thus arranged, the strand 20 is more or less pinched between the block 27 and the bar 29, thus creating resistance to the advance of 40 the strand. Should the pull on the strand increase for any reason, the strand will lift the block a little from the bar and thus diminish the resistance to advance of the strand. Means are provided to adjust the downward pressure of the 45 block. Thus the block itself may be interchangeable for others of greater or less weight; or additional weights may be piled on the block.

From the tank 24, the strand 20 passes in one or more turns 30 around the strand 9 and thence 50 through a fixed guide 31 and between a pair of

loosely meshed gears 32 and 33. From these gears the strand drops into a container 34, where it piles up and is periodically cut loose and thrown away. The guide 31 may very well be merely a forked member secured to the apparatus frame or support 35. The gear 32 is rigidly mounted on a shaft 36 rotatably supported in the support 35. The gear 33 is rotatably mounted on a shaft or pin 37 supported in a lever 38 pivoted at 39 on the support 35. An interchangeable weight 40 on the lever 38 makes it possible to adjust the grip of the gears 32 and 33 on the strand 20 passing between them. The shaft 36 and therewith the gear 32 are driven in the sense shown by arrows by any suitable power means not shown.

Back of the wiping point where the turns 30 of the strand 20 coil around the core 8, a perforated support block 41 is rigidly mounted. The coated and wiped core 8 passes directly through the block 41 from the coils 30, the coils being prevented from being dragged along by the block. While the apparatus will work fairly satisfactorily without the block 41, the wiping pressure of the coils is more easily kept constant when the wiping point is held steady by the block. The effective wiping diameter of the coils 30 varies automatically with variations in the diameter of the core, being free to follow such variations because of the tiltability of the block 21, and being compelled to follow them by the constantly maintained tension in the strand due to the pull of the gears 32 and 33 against the frictional pinch of the members 21 and 28. The coating on the coated and finished wiped strand is of uniform thickness and varying external diameter; whereas the rigid dies usually used to wipe off the excess coating material produce a coating of uniform external diameter and of thickness varying inversely with the core diameter. The thickness of the coating varies inversely with the severity of the wiping action, which in turn varies with the tension in the strand 20 at the coils 30.

In some instances also, the die 19 may be dispensed with and all the wiping done by the coils 30, provided only that the core be not run through fast enough to make the wiped off coating material pile up at the coils 30 and fall over them upon the wiped portion of the coated core. For this reason also the diameter of the wiper strand 20 will preferably be not materially smaller than the diameter of the core 8. In the particular case selected to illustrate the invention, i. e. the tinning of copper wire in a bath of molten tin, it is found that a wiper strand of ordinary textile fiber, cotton, wool, or the like, if drawn along by the gears 32 and 33 at only moderate speed, will not be charred or damagingly overheated by the hot metals even when the wire is relatively heavy and retains considerable heat during the brief transit from the molten tin of the bath to the coils 30. However, in other instances, if found necessary, as for example, where iron wire is to be galvanized in a bath of molten zinc, it may be necessary to use for the wiper strand a composite comprising a strand of cotton, linen, or the like, for tensile strength covered with threads or slivers of fibers of asbestos, or a strand of spun glass or mineral fiber. While it is found generally that the use of the oil 25 on the wiper strand is preferable, as conducing to the production of a more uniform, thin, smooth and yet continuous coating, the apparatus will work reasonably satisfactorily in some instances even if the oil be omitted from the tank 24.

A primary characterizing feature of the inven-

tion is the use of the tensioned strand 20 in one or more turns or coils 30 about the core 8 to wipe the latter. Unlike any ordinary wiping die whose effective element is a perforated solid member, the tensioned coils 30 expand and contract about a core with variations in its diameter and thus the wiping effect is substantially constant in severity and produces a uniformly thin coating since the coils act on the core with a yieldingly constrictive wiping pressure which is substantially uniform both circumferentially and longitudinally of the core. It is to be noted that this yieldingly constrictive wiping pressure is uniform under variations in diameter of the core. Large diameter portions of the core are not wiped under substantially more severe wiping pressure than are small diameter portions, as is the case where perforated blocks or plugs of rubber are used as wiper dies.

As applied in coating a core with some molten metals, e. g. tin, solder, lead, alloys of these with antimony or bismuth, and the like, it is of interest that because of the continuous advance of the wiper strand 20 longitudinally of itself through the coil or coils 30, it is possible to use the cheap strands or yarns of combustible non mineral textile fibers, cotton, wool, linen, hemp, artificial fiber and the like, for the wiper strand despite its contact with molten metal.

The embodiment disclosed and described is illustrative and may be variously modified without departing from the spirit and scope of the invention which is particularly pointed out and described in the appended claims.

What is claimed is:

1. In an apparatus for coating a longitudinally advancing core and having means to apply an excess of liquid coating material to the core, means to remove the excess coating material from the core comprising a flexible wiper strand wound in a coil about the advancing excessively coated core, means to advance the wiper strand longitudinally of itself through the coil to present fresh portions thereof to the core, and means to yieldingly tension the wiper strand throughout the coil thereof to exert a substantially constant yieldingly constrictive wiping effect on the core.

2. In an apparatus for coating a longitudinally advancing core and having means to apply an excess of liquid coating material to the core, means to remove the excess coating material from the core comprising a flexible wiper strand wound in a coil about the advancing excessively coated core, means to maintain the coil of the wiper strand stationary in position while the core passes therethrough, means to advance the wiper strand longitudinally of itself through the coil to present fresh portions thereof to the core, and means to yieldingly tension the wiper strand throughout the coil thereof to exert a substantially constant yieldingly constrictive wiping effect on the core.

3. In an apparatus for coating a longitudinally advancing core and having means to apply an excess of liquid coating material to the core, means to remove the excess coating material from the core comprising a flexible wiper strand wound in a coil about the advancing excessively coated core, means to advance the wiper strand longitudinally of itself through the coil to present fresh portions thereof to the core, means to supply lubricating material to the portion of the wiper strand advancing into the coil thereof, and means to yieldingly tension the wiper strand throughout the coil thereof to exert a substan-

75

tially constant yieldingly constrictive wiping effect on the core.

4. In an apparatus for coating a longitudinally advancing core and having means to apply an excess of liquid coating material to the core, means to remove the excess coating material from the core comprising a flexible wiper strand wound in a coil about the advancing excessively coated core, means to maintain the coil of the wiper strand stationary in position while the core passes therethrough, means to advance the wiper strand longitudinally of itself through the coil to present fresh portions thereof to the core, means to supply lubricating material to the portion of the wiper strand advancing into the coil thereof, and means to yieldingly tension the wiper strand throughout the coil thereof to exert a substantially constant yieldingly constrictive wiping effect on the core.

5. In an apparatus for coating a longitudinally advancing core and having means to apply an excess of liquid coating material to the core, means to remove the excess coating material from the core comprising a flexible wiper strand wound in a coil about the advancing excessively coated core, means to advance the wiper strand longitudinally of itself through the coil to present fresh portions thereof to the core, means to yieldingly tension the wiper strand throughout the coil thereof to exert a substantially constant yieldingly constrictive wiping effect on the core, and means to adjust the tensioning means to modify the tension.

6. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, and means to advance the wiper strand longitudinally of itself through the coil to present fresh portions thereof to the core.

7. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, means to maintain the coil of the wiper strand stationary in position while the core passes therethrough, and means to advance the wiper strand longitudinally of itself through the coil to present fresh portions thereof to the core.

8. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, means to supply lubricating material to the portion of the wiper strand advancing into the coil thereof, and means to advance the wiper strand longitudinally of itself through the coil to present fresh portions thereof to the core.

9. In an apparatus for coating a longitudinally advancing core with metal and having means to apply an excess of molten metal to the core, means to remove excess molten coating metal from the core comprising a flexible wiper strand of non-mineral textile fiber wound in a coil about

the advancing excessively coated core, means to maintain the coil of the wiper strand stationary in position while the core passes therethrough, means to supply lubricating material to the portion of the wiper strand advancing into the coil thereof, and means to advance the wiper strand longitudinally of itself through the coil to present fresh portions thereof to the core.

10. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, means to advance the wiper strand longitudinally of itself through the coil to present fresh portions thereof to the core, and means to yieldingly tension the wiper strand throughout the coil thereof to exert a substantially constant yieldingly constrictive wiping effect on the core.

11. In an apparatus for coating a longitudinally advancing core with metal and having means to apply an excess of molten metal to the core, 25 means to remove excess molten coating metal from the core comprising a flexible wiper strand of non-mineral textile fiber wound in a coil about the advancing excessively coated core, means to maintain the coil of the wiper strand stationary 30 in position while the core passes therethrough, means to advance the wiper strand longitudinally of itself through the coil to present fresh portions thereof to the core, and means to yieldingly tension the wiper strand throughout the coil 35 thereof to exert a substantially constant yieldingly constrictive wiping effect on the core.

40 12. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, means to supply lubricating material to the portion of the wiper strand advancing into the coil thereof, means to advance the wiper strand longitudinally of itself through the coil to present fresh portions thereof to the core, and means to yieldingly tension the wiper strand throughout the coil thereof to exert a substantially constant yieldingly constrictive wiping effect on the core.

13. In an apparatus for coating a longitudinally advancing core with metal and having means to apply an excess of molten metal to the core, means to remove excess molten coating metal from the core comprising a flexible wiper strand of non-mineral textile fiber wound in a coil about the advancing excessively coated core, means to maintain the coil of the wiper strand stationary in position while the core passes therethrough, means to supply lubricating material to the portion of the wiper strand advancing into the coil thereof, means to advance the wiper strand longitudinally of itself through the coil to present fresh portions thereof to the core, and means to yieldingly tension the wiper strand throughout the coil thereof to exert a substantially constant yieldingly constrictive wiping effect on the core.

Certificate of Correction

Patent No. 2,397,622.

WILSON W. REA ET AL.
